US0D1107926S

(12) **United States Design Patent** (10) **Patent No.:** **US D1,107,926 S**
(45) **Date of Patent:** **** Dec. 30, 2025**

(54) **EXTREMITY OFFLOADING DEVICE**

(71) Applicant: **MARCUS MEDICAL DEVICES, LLC**, Corona del Mar, CA (US)

(72) Inventor: **Michael J. Marcus**, Corona del Mar, CA (US)

(73) Assignee: **MARCUS MEDICAL DEVICES, LLC**, Corona del Mar, CA (US)

(**) Term: **15 Years**

(21) Appl. No.: **29/907,674**

(22) Filed: **Jan. 8, 2024**

CLAIM

The ornamental design for an extremity offloading device, as shown and described.

DESCRIPTION

FIG. 1 is a perspective view of an extremity offloading device showing my design;

FIG. 2 is another perspective view thereof;

FIG. 3 is a front elevation view thereof;

FIG. 4 is a rear elevation view thereof;

FIG. 5 is a right-side elevation view thereof;

FIG. 6 is a left-side elevation view thereof;

FIG. 7 is a top plan view thereof;

FIG. 8 is a bottom plan view thereof;

FIG. 9 is a sectional view through the line 9-9 in FIG. 3; and,

FIG. 10 is a sectional view through the line 10-10 in FIG. 7.

Evenly broken lines are used to illustrate features and/or environmental structures which form no part of the claimed design.

1 Claim, 10 Drawing Sheets
